US00D807354S

(12) **United States Design Patent** (10) Patent No.: **US D807,354 S**
Yee et al. (45) Date of Patent: ** Jan. 9, 2018

(54) **HEAD MOUNTED DISPLAY WITH FLEX CABLE**

(71) Applicant: **Oculus VR, LLC**, Menlo Park, CA (US)

(72) Inventors: **Phillip Yee**, San Francisco, CA (US); **Julian James Hammerstein**, Atherton, CA (US); **Quintin Morris**, Issaquah, WA (US)

(73) Assignee: **Oculus VR, LLC**, Menlo Park, CA (US)

(**) Term: **15 Years**

(21) Appl. No.: **29/579,870**

(22) Filed: **Oct. 4, 2016**

(51) LOC (11) Cl. **14-02**
(52) U.S. Cl. **USPC D14/372**

(58) **Field of Classification Search**

(57) **CLAIM**

The ornamental design for a head mounted display with flex cable, as shown and described.

DESCRIPTION

FIG. 1 is an isometric view of a head mounted display with flex cable showing the new design.

FIG. 2 is a left side elevation view thereof.

FIG. 3 is a right side elevation view thereof.

FIG. 4 is a front elevation view thereof.

FIG. 5 is a rear elevation view thereof.

FIG. 6 is a top plan view thereof; and,

FIG. 7 is a bottom plan view thereof.

Any broken lines in the Figures are for illustrative purposes only and form no part of the claimed design.

1 Claim, 7 Drawing Sheets
